(57) **CLAIM**

The ornamental design for a display screen with a graphical user interface for a computer-assisted orthopaedic surgical system, as shown and described.

DESCRIPTION

The patent or application file contains at least one drawing executed in color. Copies of this patent or patent application publication with color drawing(s) will be provided by the Office upon request and payment of the necessary fee.

FIG. 1 shows a first embodiment of a display screen with a graphical user interface for a computer-assisted orthopaedic surgical system;

FIG. 2 shows a second embodiment of a display screen with a graphical user interface for a computer-assisted orthopaedic surgical system;

FIG. 3 shows a third embodiment of a display screen with a graphical user interface for a computer-assisted orthopaedic surgical system;

FIG. 4 shows a fourth embodiment of a display screen with a graphical user interface for a computer-assisted orthopaedic surgical system;

FIG. 5 shows a fifth embodiment of a display screen with a graphical user interface for a computer-assisted orthopaedic surgical system; and

FIG. 6 shows a sixth embodiment of a display screen with a graphical user interface for a computer-assisted orthopaedic surgical system;

FIG. 7 shows a seventh embodiment of a display screen with a graphical user interface for a computer-assisted orthopaedic surgical system; and,

(Continued)

FIG. 8 shows an eighth embodiment of a display screen with a graphical user interface for a computer-assisted orthopaedic surgical system.

The outermost broken-line rectangle illustrates the perimeter of a display screen and forms no part of the claimed design. The remaining broken lines illustrate portions of the graphical user interface and form no part of the claimed design.
